UNITED STATES PATENT OFFICE.

PHILIP K. WILLIAMS, OF GLASTONBURY, CONNECTICUT, ASSIGNOR TO THE J. B. WILLIAMS COMPANY, OF GLASTONBURY, CONNECTICUT, A CORPORATION OF CONNECTICUT.

DESIGN FOR A CAKE OF SOAP.

51,802.

Specification for Design.

Patented Feb. 19, 1918.

Application filed December 29, 1917. Serial No. 209,587. Term of patent 14 years.

To all whom it may concern:

Be it known that I, PHILIP K. WILLIAMS, a citizen of the United States, residing at Glastonbury, in the county of Hartford and State of Connecticut, have invented a new, original, and ornamental Design for a Cake of Soap, of which the following is a specification, reference being had to the accompanying drawings, forming part hereof, in which—

Figure 1 is a perspective view of a cake of soap embodying my design.

Fig. 2 is a view in section through the same.

I claim:

The ornamental design for a cake of soap as shown.

PHILIP K. WILLIAMS.
